GRINDING MACHINE TABLE RECIPROCATING MECHANISM

Carl G. Flygare, Worcester, Mass., assignor to
Norton Company, Worcester, Mass., a corpora-
tion of Massachusetts

Application November 20, 1936, Serial No. 111,775

10 Claims. (Cl. 74—27)

The invention relates to grinding machines, and more particularly to a table reciprocating mechanism for a grinding machine.

One object of the invention is to provide a simple and thoroughly practical table reciprocating and reversing mechanism. Another object is to provide a table reversing mechanism with an improved dwell control mechanism. Another object is to provide a table reversing mechanism with a mechanism whereby a variable dwell may be obtained at each end of the table reciprocation. A further object is to provide an electrically controlled dwell control for the table reversing mechanism. A further object is to provide a table reversing mechanism with an electrical time delay relay to control the extent of dwell at each end of the table stroke. Other objects will be in part obvious or in part pointed out hereinafter. The invention accordingly consists in the features of construction, combinations of elements, and arrangements of parts, as will be exemplified in the structure to be hereinafter described, and the scope of the application of which will be indicated in the following claims.

In the accompanying drawings in which is shown one of various possible embodiments of the mechanical features of this invention,

Fig. 1 is a fragmentary front elevation of the table reversing mechanism;

Fig. 2 is a cross sectional view on the line 2—2 of Fig. 1;

Fig. 3 is a fragmentary sectional view through the table reciprocating mechanism, taken approximately on the line 3—3 of Fig. 2, showing the gears and supporting shafts in elevation;

Fig. 4 is a horizontal sectional view, taken approximately on the line 4—4 of Fig. 2, showing the gearing partly in section and partly in elevation, and also showing the reversing clutch;

Fig. 5 is a fragmentary sectional view through the reversing lever, on an enlarged scale, taken approximately on the line 5—5 of Fig. 1;

Fig. 6 is a sectional view taken approximately on the line 6—6 of Fig. 5;

Fig. 7 is a fragmentary view, showing the reversing lever and its associated parts in its left-hand end position, that is, when the table is moving toward the right;

Fig. 8 is a similar fragmentary view of the reversing lever and its associated parts in the right-hand position, as when the table is traversing toward the left;

Fig. 9 is a fragmentary sectional view, showing the means for holding the reversing clutch in a neutral position; and

Fig. 10 is a fragmentary sectional view, taken approximately on the line 10—10 of Fig. 9.

60 A grinding machine has been illustrated in the

drawings comprising a base 15 which supports a longitudinally reciprocable table 16 on a flat way 17 and a V-way (not shown). The table 16 is arranged so that it may be reciprocated by means of a power operated traversing and reversing mechanism to reciprocate a work piece in operative relation with a grinding wheel.

A power driven shaft 20 is rotatably journaled in bearings 21 and 22 in a casing 23 which is fixed within the base 10. The shaft 20 may be driven by an electric motor contained within the machine base (not shown) or any other suitable well-known driving mechanism. The shaft 20 is provided with an enlarged portion having a pair of diametrically opposed splines 24 and 25. 5 A clutch member 26 is slidably supported on the enlarged portion of the shaft 20, and is provided with clutch teeth 27 and 28 which are arranged to be thrown into engagement with clutch teeth 29 and 30, respectively. The clutch members 29 and 30 are rotatably supported on the shaft 20 and are free to rotate thereon. The clutch member 29 has formed integrally therewith a gear 31 which meshes with a gear 32. The gear 32 is fixed by a key 33 on a rotatable shaft 34 which is journaled in bearings, such as ball bearings 35, 36 and 37 in the casing 23.

The clutch member 30 has formed integral therewith a gear 40 which meshes with a rotatable intermediate gear (not shown) which in turn meshes with a gear 42 keyed to the shaft 34 by a key 43. It will be readily apparent from the foregoing that when the clutch teeth 28 are in engagement with the clutch teeth 30, as indicated in Fig. 4, the rotation of the shaft 20 will be transmitted through the clutch member 26 to the clutch teeth 28 and 30, through the gear 40, the intermediate gear (not shown), and gear 42, to rotate the shaft 34.

Similarly, when the clutch member 26 is shifted toward the left (Fig. 4) so that the clutch teeth 27 engage the clutch teeth 29, the rotation of the shaft 20 is transmitted through the clutch member 26, clutch teeth 27, clutch teeth 29, gear 31, and gear 32, to rotate the shaft 34 in the reverse direction.

In order that the rotary motion of the shaft 34 may be transmitted to cause a reciprocatory movement of the table 16, a suitable gear driving mechanism is interposed between the shaft 34 and the table 16. The shaft 34 is provided with a worm 45 which is either formed integral therewith or fixed thereto. The worm 45 meshes with a worm gear 46 which is supported on a rotatable shaft 47. The shaft 47 is journaled in bearings 48 and 49 in the casing 23. The shaft 47 also supports a small gear 50 which meshes with a large gear 51 supported on a rotatable shaft 52. The shaft 52 is journaled in bearings 53 and 54.

in the casing 23. The shaft 52 also carries a gear 55 which meshes with a gear 56 supported on a shaft 57 which is journaled in bearings 58 and 59 in the casing 23. The shaft 57 also carries a gear 60 which meshes with a rack bar 61 depending from the under side of the table 16.

It is readily apparent from the foregoing disclosure that rotary motion of the shaft 34 is transmitted through the worm 45, the worm gear 46, the gear 50, the gear 51, the gear 55, the gear 56, the gear 60, and rack bar 61, to cause a longitudinal movement of the table 16.

A clutch actuating mechanism is provided for automatically shifting the reversing clutch member 26 in timed relation with the reciprocatory movement of the table 16. A yoked member 65 is fixedly mounted on a rotatable shaft 66. The yoked member 65 is provided with rollers 67 and 68 which ride within a groove 69 on diametrically opposite sides of the clutch member 26. The rollers 67 and 68 are smaller in diameter than the width of the groove 69 to provide a lost motion between the yoked member 65 and the clutch member 26. When the shaft 66 is rocked, the yoked member 65 transmits the rocking movement to shift the clutch member 26 in the desired direction. A gear segment 69 is mounted on the end of the shaft 66. The gear segment 69 meshes with a gear segment 70 supported on the inner end of a rotatable shaft 71. The shaft 71 is journaled in bearings 72 and 73. The gear segment 70 is fixed to the end of the shaft 71 by means of a pin 74.

A reversing lever is mounted on the front end of the shaft 71. In the preferred form, the reversing lever is formed in two parts, a short lever 75 which is fixedly connected to the outer end of the shaft 71 by means of a pin 76. A table reversing lever 77 is rotatably mounted on a sleeve 78 which extends inwardly from the lever 75. The reversing lever 77 is provided with a slidably mounted member 80 which slides within an elongated slot 81 formed at the upper end of the lever 77. The slide block 80 is provided with an inwardly projecting pin 82 which is arranged in the path of a pair of reversing dogs 83 and 84, respectively, which are adjustably mounted in a T-slot 85 formed in the front surface of the table 16. By adjusting the dogs 83 and 84 longitudinally relative to the table 16, the length of the reciprocatory stroke of the table may be varied, as desired. If it is desired to move the table 16 beyond the normal reciprocatory stroke, a knob 86 formed integral with the slide block 80 may be raised vertically to lift the pin 82 out of the path of the dog 84 so that the table may be moved toward the left beyond its normal reciprocatory stroke for loading of the work piece or for truing of the grinding wheel. A safety dog 87 is also adjustably supported by the T-slot 85 and is arranged to limit the movement of the table 16 when moved beyond its normal reciprocatory stroke.

A yieldable connection is provided between the reversing lever 77 and the lever 75. The reversing lever 77 is provided with a pair of spaced studs 90 and 91, and the lever 75 is provided with a pair of equally spaced studs 92 and 93. A sleeve 94 is provided with a V-shaped surface 95 which engages the pins 90 and 92 of the levers 77 and 75, respectively. A sleeve 96 slides within the sleeve 94 and is provided at its end with a V-shaped surface 97 which engages the pins 91 and 93 of the levers 77 and 75, respectively. A spring 98 within the sleeves 94 and 96 tends normally to hold the lever 77 in alignment with the lever 75.

During reversal, however, the lever 77 may give during its movement relative to the lever 75. This movement causes a compression of the spring 98 and a telescoping of the sleeves 94 and 96.

A load and fire mechanism is provided which serves normally to hold the clutch member 26 either in engagement with the clutch teeth 29 or 30. This mechanism comprises a roller 100 which engages an arrow point member 101 carried by 10 the base 15. The roller 100 is supported by a spring pressed sleeve 102 which is slidably mounted within an arm 103 which is in turn keyed by a key 104 to the shaft 71. A compression spring 105 serves to exert a downward pressure on the 15 roller 100 to maintain it in engagement with the arrow point member 101. The mechanism above described serves as a load and fire mechanism, whereby during the period of reversal, the clutch is disengaged, during which movement the spring 20 105 is compressed as the roller 100 rides up the arrow point surface 101, after which the released compression of the spring 105 tends to shift the clutch member 26 into a reverse position.

It is desirable to provide a period of dwell at 25 each end of the table stroke in order that the grinding wheel may completely grind around the end portion of the work, that is, so that the work will rotate at least one complete rotation while the table is stationary and before the table starts 30 its movement in the reverse direction. To accomplish this result, it is desirable to provide a suitable means to disengage the clutch and to hold it in a neutral or disengaged position during 35 the period of dwell.

In order to hold the clutch in a central or neutral position, a block 110 is provided which rides in engagement with the groove 69 in the clutch member 26. The block 110 has a curved face 111 which mates with the bottom of the 40 groove 69 in the clutch member 26. The block 110 has an upper plane surface 112 which engages a plane surface 113 on the lower face of a bracket 114. The bracket 114 is fixedly mounted on the casing 26. The bracket 114 supports a 45 spring-pressed ball 115 which in a neutral position of the clutch member 26 engages a V-shaped groove 116 in the block 110 and serves to hold the clutch member 26 in a central or neutral position. The ball 115 is forced downwardly by 50 means of a spring 117 the tension of which may be adjusted by a screw 118.

In order to prevent the load and fire mechanism from shifting the clutch member 26 immediately into a reverse position, a suitable latch 55 mechanism is provided which serves to check the movement of the clutch shifting lever after the roller 100 passes the high point on the arrow surface 101. The lever 75 is provided with a downwardly extending arm 120. The lower surface of the arm 120 is provided with a notch 121 and two adjacent partial cylindrical faces 122 and 123 respectively. A spring-pressed plunger 124 backed by a spring 125 engages either the notch 121 or the surfaces 122 and 123 during the 65 operation of the machine. When the reverse lever 77 is in its extreme position, either right or left-hand as indicated in Figs. 7 and 8, the plunger 124 rides on the surfaces 122 and 123, respectively. During the period of reversal, when 70 the lever 77 is rocked by the table dogs 83 and 84, the arm 120 moves with the lever 77 and when the arm 120 has moved a sufficient distance, the plunger 124 rides off the surface 122 (Fig. 7) and the released compression of the spring 125 forces 75

the plunger 124 into the groove 121, which serves to limit the rocking movement of the reversing lever 77 and its associated parts to prevent the clutch member 26 from being shifted into the opposite position.

To produce a period of dwell of a desired but adjustable extent, a suitable dwell control mechanism is provided which is arranged to withdraw the plunger 124 after a predetermined time interval so that the released compression of the spring 105 throws the roller 100 relative to the arrow point 101 and rapidly shifts the clutch member 26 into a reverse position so as to start the table 16 moving in the opposite direction. In the preferred form, an electrical control device is provided for withdrawing the plunger 124 in timed relation with the movement of the reversing lever. A lever 130 is pivotally mounted on a stud 131 carried in a projection 132 of the base 10. The lever 130 passes through an aperture 133 in the spring-pressed plunger 124. The lever 130 is provided with an enlarged portion 135 which slides freely within the aperture or slot 134 when the lever 130 is rocked about its supporting pivot 131. The outer end of the lever 130 is connected by a stud 136 with a link 137. The lower end of the link 137 is connected by a stud 138 with an armature 139 of an electric solenoid 140. It will be readily apparent from the foregoing disclosure that when the solenoid 140 is energized, it produces a downward movement of the armature 139, thereby rocking the lever 130 in a clockwise direction (Fig. 1) to cause a downward movement of the spring-pressed plunger 124, thereby withdrawing the plunger 124 from the groove or notch 121 and allowing the released compression of the spring 105, acting on the arrow point surface 101, rapidly to shift the clutch member 26 into the reverse position and thereby start the table moving in the opposite direction.

In order to energize the solenoid 140 in timed relation with the shifting of the reverse lever 77, and to provide a period of dwell of the desired extent, a limit switch 145 is mounted on the front of the machine base. The limit switch 145 is provided with an actuating roller 146 which is carried by the arms 147. The limit switch roller 146 is arranged in the path of an adjustable screw 148 which is carried by the lever 77. The limit switch 145 is a normally open limit switch and is arranged so that when the reversing lever is moved into the position illustrated in Fig. 1, the screw 148 engaging the roller 146 rocks the limit switch to a closed position. The limit switch is connected to power lines 150.

In order to control the extent of dwell, a suitable time delay device is provided, such as an electrical time delay relay 151. The time delay relay 151 may be of any of the standard, well-known electrical time delay relays. The relay 151 is connected between the power lines 150, the limit switch 145 and the solenoid 140 in such a way that the closing of the limit switch 145 serves to set the time delay relay 151 in motion, which after a predetermined time interval operates to make a circuit to energize the solenoid 140 and thereby withdraw the spring pressed plunger 124 from the notch or groove 121 in the arm 120 so as to allow the released compression of the spring 105 rapidly to shift the clutch member 26 into a reverse position. By adjusting the time delay relay 151, a dwell of any desired extent may be obtained at the end of each table stroke.

The operation of the improved table reversing mechanism is readily apparent from the foregoing

disclosure. Assuming the table 16 to be moving in a direction toward the right, the reversing lever 77 and the associated parts are in the position illustrated in Fig. 7 and remain in this position until the dog 83 engages the pin 82 and rocks the reversing lever 77 in a clockwise direction (Fig. 7) on its supporting sleeve 78. The initial movement of the lever 77 serves through the stud 90 to compress the spring 98 until sufficient compression has been stored up to rock the lever 75 and shaft 76 against the tension of the spring 105, causing the roller 100 to ride up the surface of the arrow point 101 through the position 100a until the lever reaches and passes the high point of the arrow. When the lever 130 shifts a sufficient distance so that the surface 122 rides off from the head of the spring-pressed plunger 124, the plunger 124 is forced into engagement with the notch or groove 121 by the released compression of the spring 125. The continued movement of the table carries the roller 100 over the high point of the arrow, after which the released tension of the spring 105 causes the roller to ride down the other side of the arrow point 101 until stopped by the plunger 124 engaging the end of the notch or groove 121, thereby stopping the roller 100 in the position 100b. During this shifting movement of the lever 77 and the associated parts, the yoke 65 is rocked toward the left (Fig. 4) and after the lost motion has been taken up by rollers 67 and 68 and groove 69, shifts the clutch member 26 toward the left (Fig. 4) to disengage the clutch teeth 28 from the clutch teeth 30. When the clutch member 26 reaches its central or neutral position, the spring-pressed ball 115 (Fig. 9) engages the V-groove 116 in block 110 and holds the clutch member 26 in its neutral or central position.

When the reverse lever 77 reaches position (Fig. 1), the adjustable screw 148 engages a roller 146 and thereby closes the limit switch 145 which in turn serves to set the time delay relay 151 in operation. The electrical time delay relay 151 has been previously set for a definite time interval, after which the time delay relay serves to close a circuit to energize the solenoid 140 which in turn rocks the lever 130 in a clockwise direction (Fig. 1) to withdraw the plunger 124 from engagement with the groove 121, thereby releasing the compression of the spring 105 which rapidly shifts the roller from position 100b into position 100c and at the same time serves through the gear segments 70 and gear segment 69 to rock the yoke 65 and shift the clutch member 26 rapidly toward the left (Fig. 4) so as to throw the clutch teeth 27 into engagement with the clutch teeth 29 after the table has been held stationary for a predetermined dwell or time interval.

Similarly, the control lever 77 remains in its right-hand position during the movement of the table 16 toward the left until the dog 84 engaging the pin 82 shifts the reverse lever 77 in a counter-clockwise direction which in turn serves to shift the roller 100 from position 100c to position 100b and then into position 100a, at which point the clutch teeth 27 and 29 are disengaged and the plunger 124 is forced into engagement with the groove 121 to hold the roller 100 in the position 100a, thereby preventing shifting of the clutch member 26 into a reverse position. When the lever 77 swings from full line position (Fig. 8) in a counterclockwise direction into a vertical position, the screw 148 engaging the roller 146 of the limit switch 145 again closes the limit switch which in turn sets the electrical time delay relay 75

151 in operation. The relay 151, after a predetermined set time interval, makes a circuit to energize solenoid 140 which in turn again withdraws the plunger 124 from engagement with the 5 notch 121 and allows the roller 100 to move from position 100a into position 100 (Fig. 8), thereby shifting the clutch member 26 toward the right to engage the clutch teeth 28 with the clutch teeth 30 and thereby start the table moving in a direction toward the right after a predetermined period 10 of dwell.

It will thus be seen that there has been provided by this invention apparatus in which the various objects hereinabove set forth together 15 with many thoroughly practical advantages are successfully achieved. As many possible embodiments may be made of the above invention and as many changes might be made in the embodiment above set forth, it is to be understood that 20 all matter hereinbefore set forth or shown in the accompanying drawings is to be interpreted as illustrative and not in a limiting sense.

I claim:—

1. In a grinding machine, a longitudinally reciprocable table, means to reciprocate said table, means including a lever to stop said table movement, adjustable dogs on said table to actuate said lever, and an electrically controlled mechanism to start movement of the table in the reverse direction after a predetermined period of dwell.

2. In a grinding machine, a longitudinally reciprocable table, means to reciprocate said table, means including a lever to stop said table movement, adjustable dogs on said table to actuate said lever, and an electrically controlled mechanism which is actuated in timed relation with said lever to start the table moving in the reverse direction after a predetermined time interval.

3. In a grinding machine, a longitudinally reciprocable table, means including a lever to stop said table movement, adjustable dogs on said table to actuate said lever, and an electrically controlled mechanism including a limit switch actuated by said lever, an electrical time delay relay which is set in motion by said switch, and a solenoid which is energized by said time delay relay after a predetermined time interval to start the 50 table moving in the reverse direction.

4. In a grinding machine, a longitudinally reciprocable table, mechanism including a clutch to reciprocate said table, a reversing lever to disengage said clutch, adjustable table dogs to actuate said lever, and an electrically controlled clutch actuating mechanism which is arranged to throw said clutch into a reverse position after a predetermined period of dwell to start the table moving in the reverse direction.

5. In a grinding machine, a base, a longitudinally reciprocable table, mechanism including a reversing clutch to reciprocate said table, means including a reversing lever and table dogs to disengage said clutch, means to hold said clutch in a neutral position, and an electrically controlled mechanism which is actuated in timed relation with said reverse lever to shift the clutch into a reverse position after a predetermined time interval.

6. In a grinding machine, a base, a longitudinally reciprocable table, means including a reversing clutch to reciprocate said table, a re-

versing lever arranged to disengage said clutch, adjustable table dogs to actuate said lever, a dwell control mechanism to cause an adjustable period of dwell at the end of the table stroke including an electric switch actuated in timed relation with said reverse lever, a time delay relay controlled by said switch, and a solenoid which is controlled by said relay to shift said clutch into a reverse position after a predetermined time interval.

7. In a grinding machine, a base, a longitudinally reciprocable table, means including a rack and gear mechanism to reciprocate said table, means including a clutch to reverse the direction of movement of said gear mechanism, means including a reversing lever and adjustable table dogs to disengage said clutch, and an electrically controlled mechanism including a limit switch actuated by said reverse lever, an adjustable electrical time delay relay which is set in motion by said switch, and a solenoid which is energized by said time delay relay after a predetermined time interval to throw said clutch into a reverse position to reverse the direction of movement of said table.

8. In a grinding machine, a base, a longitudinally reciprocable table, means including a rack and gear mechanism to reciprocate said table, a clutch to reverse the direction of movement of said gear mechanism, means including a reversing lever to disengage said clutch, adjustable table dogs to actuate said reversing lever, a spring-pressed plunger to hold said clutch in a neutral position, and an electrical dwell control mechanism including a solenoid operatively connected to withdraw said plunger and thereby shift said clutch into a reverse position to change the direction of movement of said table.

9. In a grinding machine, a base, a longitudinally reciprocable table, means including a rack and gear mechanism to reciprocate said table, a clutch to reverse the direction of movement of said gear mechanism, means including a reversing lever and table dogs to disengage said clutch at the end of a table reciprocation, a spring-pressed plunger to hold said clutch in a neutral position, and an electrical time delay mechanism including a switch actuated by said reversing lever, an electrical time delay relay operated thereby, and a solenoid energized thereby after a predetermined time interval to throw said clutch into a reverse position after a predetermined period of dwell.

10. In a grinding machine, a base, a longitudinally reciprocable table, means including a rack and gear mechanism to reciprocate said table, a clutch to reverse the direction of movement of said gear mechanism, a load and fire mechanism arranged normally to hold said clutch in one of two operating positions, means including a reversing lever and table dogs to disengage said clutch at the end of a table reciprocation, a spring-pressed plunger to hold said clutch in a neutral position, and an electrical time delay mechanism including a switch actuated by said reverse lever, an electrical time delay relay operated thereby, and a solenoid energized by said relay after a predetermined time interval to withdraw said plunger and allow the load and fire mechanism to throw the clutch into a reverse position after a predetermined period of dwell.
